HANGER AND SPACER BRACKET

Filed March 12, 1948

UNITED STATES PATENT OFFICE

2,665,869

HANGER AND SPACER BRACKET

Martin L. Samuels, Chicago, Ill., assignor to Reflector Hardware Corporation, Chicago, Ill., a corporation of Illinois

Application March 12, 1948, Serial No. 14,402

3 Claims. (Cl. 248—214)

1

This invention relates to improvements in merchandise display devices and has as a particular object to provide means by which a clip or bracket can be easily and effectively attached to a horizontal bar or cross-support in such manner that the bracket will not accidentally slide lengthwise of the bar nor accidentally be released therefrom.

Another object is to provide an extension for the bracket which is usable as a hanger or as a spacer and which serves as a handle by which to attach the bracket to a cross-support. Another object is to provide a bracket which can be wedgingly secured as result of swinging motion of the bracket toward its support. Another object is to provide for a somewhat resilient wedging action for securely fixing the bracket.

Another object is to provide wedging action by means of a bulging projection or bulging projections arranged on an inclined member in such manner as to provide for a springy snap-over-and-lock action which increases the frictional engagement of the bracket with the top and bottom surfaces of the bar. Another object is to provide a device which can be formed from sheet metal by stamping, bending, and punching operations.

The invention has found valuable application for spacer elements adapted when used in pairs to support tires in upright display position.

Objects, features and advantages of the invention will be set forth in the drawings, and in said drawings:

Fig. 1 is a perspective view showing the invention applied to a tire display rack;

Fig. 2 is a vertical section approximately on line 2—2 of Fig. 1;

Fig. 3 is a rear elevation of the bracket of Fig. 2;

Fig. 4 is a vertical section through modified form of bracket;

Fig. 5 is a rear elevation of the bracket of Fig. 4;

Fig. 6 is an enlarged view showing the attaching action of the bracket; and

Fig. 7 is an enlarged view showing the attaching action of a modified form of bracket.

Fig. 1 is a perspective view showing how the present invention is applied to hold spacer rods on a horizontal bar. Numerals 1 and 2 indicate two uprights, in this instance of channel bar formation connected, as to the floor, in any suitable manner not shown. Each of these channels has two vertical rows of slots 3—4 adapted to have interlocking engaged therewith, horizontal members 6 and diagonal members 7 for forming a rack. Each member 6 has suitable means

2

not shown which fits in and interlocks with one of the slots of the row 4. These horizontal members are supported at their outer ends by the diagonal element 1, each suitably connected at the upper end by means entering one of the slots of the row 4, and connected at the opposite end by suitable means 8, with corresponding horizontal member 6. The connections of only one of the bars 7 has been shown, and only the position of the opposite bar 7 has been indicated. The tops of the bars 6 are notched as at 9, and laid in these notches are somewhat L-shaped horizontal bars 10. There are two of these weight-supporting bars, and the periphery of a tire may be supported on them, and as so supported the tire may enter between horizontal spacer elements or arms 11 each of which is attached to a bracket 12 of this invention.

Now referring to Fig. 2. The clips 12 are supported on a horizontal bar 14. In Fig. 1 this bar is suitably connected at each end with one of the slots of the row of slot 4. However, this bar 14 may be connected in any suitable manner and the device of this invention may be used in relation thereto for preventing the bracket or clip from accidentally moving lengthwise of the bar. The bar is convexly curved as at 15.

The bracket is so formed as to provide a hooked structure at its top and this is done by bending a plate to provide a horizontal portion 16 adapted to engage the top of the bar, and a downwardly directed rear portion 17. The body portion 18 of the bracket engages the front face of the bar 14 as shown, and has formed thereon a convexity 19 which may be formed by punching. Suitably welded to this convexity and to the outer surface 18 is a terminal plate or base of the arm 11, which arm as before stated may be used as a hook or hanger or as a spacer bar, as in Fig. 1. The arm serves as a handle by which to manipulate the bracket to attach it. The body portion 18 of the bracket has openings 21 therein through which fastening devices can be passed to secure the bracket to the wall.

The unique part of this invention in combination with the hook is the provision of a structure at the bottom of the bracket which is adapted to engage the bottom of the bar to increase the frictional engagement of the bracket with the top and bottom surfaces of the bar. To this end the bottom of the bracket has a bent-back portion or lip 25, the upper surface of which makes an angle of about 20 degrees with the inner surface of the body 18. This wedging lip 25 is provided, in Figs. 2 and 3, with a pair of punched-

up bulges or convexities 26, and the relation of the middles of these bulges, as represented by line A—A, to the vertical center line B—B of the support 14, and the relation to the inner surface 27 of the hook to the bulges are important.

The bracket is held in the position of Fig. 2 by wedging frictional action and in a manner which may be said to result from a snap-over-and-lock action. It will be noted that line A—A lies rearwardly beyond line B—B in direction of the arrow C, which represents the direction of swing of the bracket on its way to the final position of Fig. 2.

The hook-over and lowering actions of the device are shown in the enlarged view Fig. 6. The bracket is first brought approximately to the full line position of this figure in which position the forward end 30 of the extension 25 may clear the bottom of the bar. The clip is then moved downwardly and at the same time swung inwardly as represented by the arrow D, and finally, as a result of the compound action, arrives at the position shown in dot-and-dash lines whereat the surface 27 of the hook is engaged with the top surface of the bar and the bulges 26 are engaged with the bottom of the bar. On continued swinging motion from the dot-and-dash line position, a snap-over-and-lock action occurs, and the reference line A—A passes across the line B—B to the position shown in Fig. 2 whereat the device is frictionally locked. The extension or lip 25 preferably has a resilient action to the extent that it will give slightly downwardly as snap-over-locking action occurs during rearward swinging movement of the bracket to the final position of Fig. 2. After passage of the top of the bulge 26 across the line B—B there is a recoil action of this extension 25 which makes for a secure anchorage. Insofar as I am aware no such snap-over-and-lock action has ever before been conceived of in a device of this kind. This resilient action materially reduces the frictional wear between the bulge or bulges and the lower surface of the bar 14. To provide wedging action by means of projections arranged on an inclined surface the parts must have a certain critical relation to the dimensional thickness and height of a bar.

In Fig. 4 a modification has been shown in all respects substantially like that previously described except that only a single convex bulge 32 is provided and it is elongated as shown in Fig. 5.

In Fig. 7 has been shown a modification in which no bulge is used on the wedging lip and in which the angular relation of the upper surface of the wedging lip or extension 36 to the inner surface 37 of the body 18 is less than 20°, and may be about 15°. In this case also frictional engagement between the bracket and the bar is obtained. The figure shows the position of the parts as just before the final swing of the bracket to bring the surface 37 against the opposed face 38 of the bar 14. In this case the wedging action takes place at the corner 39 of the bar and in relation to that part of the wedging surface 40 which lies between this corner

39 and the surface 37. In this instance the extension 36 need not be as long as the extension 25. It will be understood that when the parts are in the position shown in Fig. 7 the surface 27 of the hook will substantially be engaged with the top surface of the bar 14. The angle of the top surface of the extension 36 may be more acute than is shown. When weight is applied to the rod 11, wedging action is increased.

The snap-over construction is the preferred construction although as will be clearly seen that friction wedging action is obtained in both forms.

What I claim is:

1. In combination with a bar which has top and bottom surfaces, the bottom surface being convex, a bracket having an upstanding relatively flat body portion, a hook including a first member extending rearwardly from the upper end of said body portion over the top surface of said bar and a second depending member extending downwardly behind said bar substantially parallel to said body portion, said hook pivotally supporting said bracket over the top surface of said bar, a substantially flat resilient member extending rearwardly from the lower end of said body portion, and embossed means formed on the upper surface of said flat member which solely engages said convex bottom surface of said bar to secure said bracket against sliding movement along said bar, said embossed means including a rounded portion which is in strong frictional relation with said convex surface and which slides on said convex surface in a direction transverse to the longitudinal direction of said bar as the lower end of said body portion of said bracket is pivoted toward and away from said bar.

2. The combination set forth in claim 1, wherein said substantially flat resilient member extends rearwardly from the lower end of said body portion at an angle of more than ninety degrees.

3. The combination set forth in claim 1, wherein a plurality of spaced-apart embossed means are formed on the upper surface of said flat resilient member.

MARTIN L. SAMUELS.
